ATTORNEY'S

UNITED STATES PATENT OFFICE.

ORMOND M. LISSAK, OF WESTPOINT, NEW YORK.

CARTRIDGE-VENT DETECTOR.

No. 800,311.

Specification of Letters Patent.

Patented Sept. 26, 1905.

Application filed September 20, 1904. Serial No. 225,218.

To all whom it may concern:

Be it known that I, ORMOND M. LISSAK, a citizen of the United States, residing at Westpoint, county of Orange, and State of New York, have invented a new and useful Improvement in Cartridge-Vent Detectors, of which the following is a full, clear, and exact description, reference being had to the accompanying drawings, which form a part 10 of this specification.

In the manufacture of cartridges and the like in which a primary charge is used it is essential that there should be a vent, so that the explosion of the primary charge will be 15 communicated through this vent to the explosive material. In the manufacture of cartridges a vent is formed before the primary charge is added.

The object of my invention is to provide 20 mechanism which will automatically test the cartridge and determine whether the vent has been formed and properly formed before the primer is inserted.

I will first describe the specific mechanism 25 for carrying out my invention illustrated in the accompanying drawings and then point out the invention in the claims.

In the drawings, Figure 1 is a top plan view. Fig. 2 is an elevation. Fig. 3 is an 30 elevation of a detail. Fig. 4 is another elevation, partially in section, of Fig. 3. Fig. 5 is a plan view of Figs. 3 and 4.

I have illustrated my invention as applied 35 to a priming-machine of the well-known character, and its specific construction and mode of operation need not herein be specifically described, as it forms no part of my invention.

A is a rotary table; B B', the curved fixed 40 walls, forming between them the channel B².

C is the rotary priming-table, which is given a step-by-step rotary movement by the well-known mechanism. (Not shown.) On this table are the grooves or pockets c 45 for the reception of the cartridges. The cartridges in the rotation of the table by means of the guides or channel B² are brought opposite and contiguous to one of the pockets c and are injected therein by the ram D sliding in groove d. This ram has the slotted bell-crank lever d', pivoted at d³, connected to a spring d², which normally holds it in its outward position. The ram is intermittently retracted to allow a cartridge to pass 50 in front of it by means of the lever d⁴, working in a slot d⁵ in the frame of the machine.

This lever is pivoted at d⁶ and intermittently operated in the well-known manner by means of a cam d⁷ on shaft d⁸, driven by mechanism, (not shown,) so that as a cartridge approaches the plate D the rod d⁴ strikes the lever d', retracting the ram against the action of spring d², and thus allowing a cartridge to come in front of plate D. When the lever d⁴ is moved in the opposite direction, the 65 spring d² again becomes active and moves the plate D outward, forcing one of the cartridges into a pocket c, the strength of the spring being, as is well known, just sufficient to force the cartridge into the pocket. All 70 this is of old and well-known construction.

Mounted so as to move longitudinally upon the vertical rods E and E', secured to the frame of the machine, is the frame F. Projecting from the frame F is the bracket 75 f^x, to which the rod f' is secured by a pin passing through the rod into the bracket. The rod f' at the other end is secured in a similar manner to the bar f², which is rigidly connected to the crank f³, mounted upon the 80 crank-pin f⁴. This crank is operated by a cam f⁶ on shaft d⁸, so that it is given a movement which will cause the frame F to move on the rods E E' when the priming-table is at rest.

G is a guide connected to the frame F, in which moves the piston H, having at its outer end the pin h. Surrounding the piston H is a spiral spring h². The arrangement and position of the parts are such that in the 90 movement of the frame F the pin h moves in alinement with the vent-opening in the cartridge. If the vent-opening be properly made, the pin is of such size that it passes through the vent, and the piston H and 95 frame F have no movement independent of each other. When, however, the vent is not made or not properly made, the pin strikes the metal, and in the further forward movement of the frame the pin does not move, 100 causing a relative backward movement of the piston H. I indicate this last condition, and thus the lack of vent or proper vent, in the following manner: J is a battery. Any 105 other source of current-supply may be used. The wire j runs from one pole of this battery and is connected to a part of the machine in electrical connection with frame F, and therefore with plunger H. The wire j' from the other pole of the battery is connected to the 110 plate K, carried by, but electrically insulated from, the frame F. Projecting from

this plate K is the spring-arm L, which projects in line with the rear end of plunger H. With a vent formed and properly formed in the movement of frame F the plunger and frame move in unison, and the plunger H does not contact with the spring-arm L. If, however, the vent is not formed or is not properly formed, in the forward movement of the frame F the pin h will strike the cartridge metal, holding the plunger H from further movement, and there will be a relative movement of the plunger with reference to the frame, compressing spring h³ and causing the plunger to contact with the spring-arm L, and the circuit will be closed. During the retracting movement of the frame F the spring h³ returns the piston H to its normal position and breaks the electrical circuit. I can place any desired indicating device in this circuit which will indicate when this result occurs. I have shown a bell M, which will ring when this occurs, and the circuit is closed. In order to hold the cartridge with certainty in the position to be in proper alinement with the plunger H, I employ a guide N, mounted on the end of rod E and on stud n, provided with a projecting spring N'. When in the rotation of the table the cartridge reaches the guide, the spring holds it in such position in the pocket as to be in alinement with plunger movement. When the bell rings, it indicates a cartridge without a vent or with an imperfect vent, and such cartridge may readily be removed by moving the guide N, covering the mouth of the pockets c from the end of rod E and stud n, and by hand the defective cartridge may be removed.

Having now fully described my invention, 40 what I claim, and desire to protect by Letters Patent, is—

1. In a vent-detector, the combination, with a support for a cartridge, of an electric circuit normally open, there being a circuit-closer in said circuit in line with the vent of a cartridge upon said support, means to reciprocate said circuit-closer toward and from and in line of said vent, a support for said circuit-closer in which said circuit-closer has a movement to close its circuit when in its reciprocation it strikes an obstruction.

2. In a vent-detector, the combination, with a support for a cartridge, of an electric circuit, there being a circuit-closer in said circuit, means to reciprocate said circuit-closer in line with the vent of a cartridge upon said support, and means to operate said circuit-closer to close the circuit when the circuit-closer, in its reciprocation, meets an obstruction.

3. In a vent-detector, the combination with a support for a cartridge, of an electric circuit, normally open, having thereon a circuit-closer comprising a frame, a guide, a piston in said guide, a pin connected to said piston, means to reciprocate said frame, with said pin in line with the vent of a cartridge upon said support, and connection whereby said circuit is closed when said pin meets an obstruction and said piston moves in said guide.

ton, means to reciprocate said frame, with said pin in line with the vent of a cartridge upon said support, and connection whereby said circuit is closed when said pin meets an obstruction and said piston moves in said guide.

4. In a vent-detector, the combination, with a support for a cartridge, of a frame, a guide, a piston in said guide, a pin connected to said piston, means to reciprocate said frame, with said pin in line with the vent of a cartridge upon said support, an electric circuit, one pole of which is electrically connected with said frame, a plate carried by, but insulated from, said frame, said plate being in line of said piston and adapted to contact therewith when said piston moves in the guide.

5. The combination, with a table provided with a plurality of cartridge-holders, means to rotate said table intermittently, a vent-detector and means to reciprocate said vent-detector, the position of the vent-detector being such that when the table is at rest it is in line with a cartridge-holder.

6. The combination, with a table provided with a plurality of cartridge-holders, means to rotate said table intermittently, a vent-detector and means to reciprocate said vent-detector, the position of the vent-detector being such that when the table is at rest it is in line with a cartridge-holder, and means adapted to hold said cartridge in the holder in line with the vent-detector.

7. The combination, with a table provided with a plurality of cartridge-holders, means to rotate said table intermittently, a vent-detector and means to reciprocate said vent-detector, the position of the vent-detector being such that when the table is at rest it is in line with a cartridge-holder, a guide adapted to hold the cartridge in said holder in line with the vent-detector.

8. The combination, with a table, provided with a plurality of cartridge-holders, means to rotate said table intermittently, an electric circuit, normally open, there being a circuit-closer in said circuit, means to reciprocate said circuit-closer, said circuit-closer being connected whereby when the circuit-closer in its reciprocation meets an obstruction the circuit is closed, the position of the circuit-closer being such that when the table is at rest it is in line with a cartridge-holder.

9. The combination, with a table provided with a plurality of cartridge-holders, means to rotate said table intermittently, a circuit-closer, and means to reciprocate said circuit-closer, an electric circuit controlled by said circuit-closer the position of the circuit-closer being such that when the table is at rest it is in line with a cartridge-holder, and means adapted to hold said cartridge in the holder in line with the circuit-closer.

10. The combination, with a table pro-

vided with a plurality of cartridge-holders, means to rotate said table intermittently, a circuit-closer and means to reciprocate said circuit-closer, an electric circuit controlled by 5 said circuit-closer the position of the circuit-closer being such that when the table is at rest it is in line with the cartridge-holder, a guide adapted to hold the cartridge in said holder in line with the circuit-closer.

10 11. The combination, with a table, provided with a plurality of cartridge-holders, means to rotate said table intermittently, an electric circuit, normally open, there being a circuit-closer in said circuit, means to reciprocate 15 said circuit-closer when said table is at rest, said circuit-closer having connection whereby when the circuit-closer in its reciprocation meets an obstruction the circuit is closed, the position of the circuit-closer being such that when the table is at rest it is in 20 line with a cartridge-holder.

12. The combination, with a table, provided with a plurality of cartridge-holders, means to rotate said table intermittently, an 25 electric circuit, normally open, there being a circuit-closer in said circuit, means to recip-

rocate said circuit-closer when said table is at rest, said circuit-closer having connection whereby when the circuit-closer in its reciprocation meets an obstruction the circuit is 30 closed, the position of the circuit-closer being such that when the table is at rest it is in line with a cartridge-holder, and a guide adapted to hold the cartridges in said holder in line with the circuit-closer.

35 13. The combination, with a table provided with a plurality of cartridge-holders, means to rotate said table intermittently, a circuit-closer an electric circuit controlled by said circuit-closer and means to reciprocate 40 said circuit-closer, the position of the circuit-closer being such that when the table is at rest it is in line with the cartridge-holder, a guide adapted to hold the cartridges in said holder in line with the circuit-closer.

45 In testimony of which invention I have hereunto set my hand, at Westpoint, on this 2d day of September, 1904.
